Frank D. Faradix

FRANK D. PARADIS, OF CHICAGO, ILLINOIS.

Letters Patent No. 88,201, dated March 23, 1869.

IMPROVED WASHING-MACHINE.

The Schedule referred to in these Letters Patent and making part of the same.

To all whom it may concern:

Be it known that I, FRANK D. PARADIS, of the city of Chicago, in the county of Cook, and State of Illinois, have invented certain new and useful Improvements in Washing-Machines; and I do declare that the following is a full, clear, and exact description thereof, reference being had to the accompanying drawings, making part of this specification, in which—

Figure 1 is a top view of my device placed on a tub.

Figure 2, a side view.

Figure 3, a rear-end view.

Figures 4 and 5, details of the irons H.

The object of my invention is to construct a cheap and efficient device to be used in washing clothes, which can be used with an ordinary tub, as a receptacle for the water and clothes, and easily detachable therefrom.

To enable others skilled in the art to make and use my invention, I proceed to describe its construction and operation.

A A represent two strips of wood, each about two feet long, from two to three inches wide, and from one and a half to two inches thick, and placed about twelve inches apart, the size and relative position depending somewhat on the size of the tub with which the device is to be used.

B is a piece of board, about eight inches wide, placed between the two strips A A, and somewhat inclined, as seen in fig. 2, and so located as to leave a sufficient space between it and the side of the tub T, for the clothes to pass through. This board may be permanently connected to A A, or may be so arranged and connected as to be removable.

C is a piece of zinc, one end of which is secured to the inner edge of B, and the opposite end is secured to a round piece, g and i, which is supported by springs c c, connected at one end to the roller i, and at the other end to the strips A A. This zinc C is bent down under the cylinder E, as shown in fig. 2, and the springs c c allow it to yield as may be necessary in use.

D is a board secured to the top of the pieces A, over the zinc C. It serves the purpose of strengthening the device, keeping the strips A A in their proper position, and it affords a convenient place to lay the clothes when taken out, after having been run through the machine.

E is a corrugated cylinder of wood, about six or seven inches in diameter; it may be solid or hollow. As shown, the corrugations are somewhat winding. The cylinder should, for durability, be covered with zinc fitted to the corrugations.

F and G are gear-wheels, for operating the machine. F may be about nine or ten inches in diameter, and G about six inches in diameter. The former runs on a pin secured to the board D, or to the piece f. The latter is secured in the usual manner upon a pin connected with the cylinder, and running in the bearing e.

d is a pin inserted in F, and used for turning the same.

H represents an iron attached to each end of the strips A, for the purpose of supporting the device upon the tub T.

The ends of A are cut beveling, so as to fit the tub, and the irons H are so formed as to fit the ends of A. They may be permanently secured, or each iron may have a slot, h, and be secured to the strips A by means of a set-screw, g. When so made, the same machine can be used upon tubs of different sizes.

The board B may have a place, a, at one end, for holding soap, and the other end b may be made like a wash-board, and covered with zinc, upon which those parts of the clothes, which may not be thoroughly cleaned in the machine, may be rubbed with the hands.

The device should be so constructed and arranged, that when in use, the lower portion of the cylinder E will be constantly in the water.

In use, my device is to be placed over, and in and upon an ordinary wash-tub, having water enough to partially cover the cylinder E. The article to be washed is to be laid upon the zinc C, so as to be drawn under the cylinder when put in motion.

The operator can, with one hand, turn the machine, and with the other, hold the article being washed, to prevent it from being drawn too rapidly under the cylinder; and, being so held, each and every part of such article can be subjected to the action of the cylinder as long as may be desired, the suds being forced rapidly and continuously through the cloth, the same being at the same time rubbed, and pressed between the cylinder and zinc sheet C.

When the article has been sufficiently rubbed, it may be permitted to pass through the machine, or may be withdrawn from the front, at the same time keeping the cylinder in motion, and thus, when withdrawn, but little water will remain in the clothes.

Several small pieces may be run through at the same time.

I do not confine myself to the form of gearing described.

Washing-machines, as usually constructed, are handled with difficulty, occupy considerable room, and in summer are liable to become leaky. My device obviates these objections, and has other manifest advantages.

Having thus fully described my invention, What I claim as new, and desire to secure by Letters Patent, is as follows:

The bars, or pieces A, supporting-irons H, cylinder E, zinc sheet C, springs c, and gear-wheels F G, when combined, and arranged, and constructed, and operating substantially as and for the purposes specified.

FRANK D. PARADIS.
